UNITED STATES PATENT OFFICE

RANDOLF A. MIKALSEN, OF BROOKLYN, NEW YORK

CLEAN-OUT FOR PIPES

Application filed August 28, 1931. Serial No. 559,970.

An object of the invention is to provide a clean-out for pipes which is inexpensive to manufacture and which may be conveniently used to remove obstructions in pipes and conduits.

Another object of the invention is to provide a device of the character described in which a body member may be moved against an obstruction, and jaws mounted on the body member may be moved forwardly to close in the front of the body member to grip the obstruction which has been engaged by the body member.

Still another object of the invention is to mount the jaws on a body member having sides with ends, the sides being connected by a web portion with curved ends which assist the movement of the device around bends in the pipe or conduit.

The invention furthermore comprehends a clean out for pipes in which resilient means are provided to rotate and close the jaws on pivotal means connecting the jaws with the body member, a catch held in operative position by a trigger being provided to hold the jaws in open position and means being provided to pull the trigger to permit the escape of the jaws from the catch.

Additional objects of the invention will appear in the following specification in which the preferred form of the invention is described.

In the drawing similar reference characters refer to similar parts in all the views in which—

Figure 1 shows a section of a pipe in which the device is positioned.

Figure 2 is a sectional view on the line 2—2 of Figure 1, and

Figure 3 is a cross section of the pipe showing the forward end view of the device.

By referring to the drawing, it will be seen that the body member 5 has a web 6 which connects the sides 7; the edges of the ends 8 of the sides 7 are converged, as best illustrated in Figure 2 of the drawing, and the edges of the web 6 also converge at the ends 9 of the said web member 6. This construction is provided so that the body member 5 may move readily through the interior of a

pipe or conduit 10 and around bends and curves in the said pipe or conduit.

Mounted on the body member 5, there are two jaws 11, one of these jaws 11 being disposed at each side of the web member 6, the jaws being pivoted at 12 to the sides 7 of the body member 5. The pivots 12 are disposed near the forward end 13 of the body member 5 so that when the jaw members are in open position they may be disposed as shown by the full lines in Figure 2 of the drawing, but when the jaw members are in closed position, they may extend in front of the forward end of the web member 6, as illustrated by the dotted lines in the said figure. Springs 14 are mounted on the pivots 12 and the ends of these springs engage the web 6 and the jaws 11 to move the jaws 11 to closed position.

The web 6 has a guide slot 15 in which is disposed a catch 16, the catch 16 having flanges 17 engaging the opposite sides of the web 6, the catch 16 also having ends 18 which are positioned for holding the jaws 11 in open position. It will be seen by referring to Figure 2 of the drawing that the ends 18 have diverging edges 19 which engage the jaws 11 so that when the catch 16 is not pressed in the direction of the jaws 11, the springs 14 will serve to move the jaws to free the jaws from the catch 16, and to continue to move the jaws to closed position, as illustrated by the dotted lines in Figure 2 of the drawing.

Pivoted to the web 6 of the body member 5 at 20 there is a trigger 21 which is positioned to engage the catch 16 and hold the catch in operative position with the jaws 11 in open position. Secured to this trigger 21, there is a lanyard 22, and secured to the body member 5, there is a flexible member 23, so that the body member 5 may be moved in the pipe or conduit 10 by the flexible member 23, and when the forward edge of the web 6 engages the obstruction 24 in the pipe or conduit 10, the lanyard 22 may be pulled, which will free the trigger from the catch 16, thereby permitting the jaws 11 to move the catch 16 rearwardly, and the jaws to move to closed position and to grip the obstruction 24. The body member 5 may then be withdrawn from

the pipe or conduit 10 carrying with it the obstruction or a portion thereof when, if necessary, the device may be used again to withdraw all portions of the obstruction.

What is claimed:

- 5 1. In a device of the class described, a body member having a projection for engaging an obstruction at its forward end, jaws movably mounted on the body member, means movable relatively to the projection for holding the jaws at the rear of the forward edge of the body member, means for moving the jaws forwardly for engaging the obstruction at the front of the body member, and means for releasing the first mentioned means.
- 10 2. In a device of the class described, a body member having a projection for engaging an obstruction at its forward end, jaws movably mounted on the body member, means movable relatively to the projection for holding the jaws at the rear of the forward edge of the body member, resilient means for moving the jaws forwardly for engaging the obstruction at the front of the body member, and means for releasing the first mentioned means.
- 15 3. In a device of the class described, a body member for engaging an obstruction at its forward end, jaws movably mounted on the body member, means for holding the jaws at the rear of the forward edge of the body member, means for moving the jaws forwardly for engaging the obstruction at the front of the body member, a flexible member secured to the body member for moving the body member in a pipe and a lanyard secured to the first mentioned means for operating the latter.
- 20 4. In a device of the class described, a body member having a projection for engaging an obstruction at its forward end, jaws pivoted to the body member for movement from positions at the rear of the forward end of the body member to positions at the front of the said forward end, resilient means for moving the jaws forwardly, a trigger means movable relatively to the body member for holding the jaws rearwardly of the said forward end, a flexible member secured to the body member for moving the latter in a pipe and means to operate the trigger means.
- 25 5. In a device of the class described, a body member having sides connected by a web portion, the edges of the sides and the web portion converging at their ends, two jaws, one mounted at each side of the web portion, and means to move the jaws together to grip an obstruction.
- 30 6. In a device of the class described, a body member having sides connected by a web portion, the edges of the sides and the web portion converging at their ends, two jaws, one mounted at each side of the web portion, and means to move the jaws from the rear of the

forward end of the body member to closed position in front of the said forward end.

7. In a device of the class described, a body member having sides connected by a web portion, the edges of the sides and the web portion converging at their ends, two jaws, one pivoted at each side of the web portion, resilient means for holding the jaws in closed position, and means for holding the jaws in open position.

8. In a device of the class described, a body member having sides connected by a web portion, the edges of the sides and the web portion converging at their ends, two jaws, one pivoted at each side of the web portion, resilient means for holding the jaws in closed position, means for holding the jaws in open position, a flexible member secured to the body member, and a lanyard secured to the second mentioned means for operating the latter.

9. In a device of the class described, a body member having sides connected by a web portion, the edges of the sides and the web portion converging at their ends, two jaws, one disposed at each side of the web portion, the jaws being pivoted to the sides, resilient means for holding the jaws in closed position, and means for holding the jaws in open position.

10. In a device of the class described, a body member having a guideway, two jaws movably mounted on the body member, resilient means for holding the jaws in closed position, a catch movable in the guideway and having means for holding the jaws in open position, a trigger mounted on the body member for holding the catch in operative position, a flexible member secured to the body member and means for freeing the trigger from the catch to permit the jaws to close.

11. In a device of the class described, a body member having a web with a guideway and sides, two jaws, one disposed at each side of the web, the jaws being pivoted to the sides, resilient means for moving the jaws to closed position, a catch movable in the guideway and having means for holding the jaws in open position, a trigger mounted on the body member for holding the catch in operative position, a flexible member secured to the body member and means for freeing the trigger from the catch to permit the jaws to close.

12. In a device of the class described, a body member having a web with a guideway and sides, two jaws disposed one at each side of the web, the jaws being pivoted to the sides and being adapted to move from the rear of the forward portion of the body member to positions in front of the body member, resilient means for moving the jaws forwardly to closed position, a catch movable in the guideway and having means for holding the jaws in open position, a trigger mounted on the body member for holding the catch in

operative position, a flexible member secured to the body member and means for freeing the trigger from the catch to permit the jaws to close.

5 13. In a device of the class described, a body having sides connected by a web, there being a guideway in the web, the ends of the edges of the web and the sides converging, two jaws disposed one at each side of the web, the jaws being pivoted to the sides and being adapted to move from the rear of the forward portion of the body member to positions in front of the body member, resilient means for moving the jaws forwardly to 10 closed position, a catch movable in the guideway and having means for holding the jaws in open position, a trigger mounted on the body member for holding the catch in operative position, a flexible member secured to the body member and means for freeing the trigger from the catch to permit the jaws to close.

15 14. In a device of the class described, a body member having sides extending at an angle to and connected by a web, two jaws, 20 one movably disposed at each side of the web, the jaws being disposed between the sides to prevent the contact of the jaws with the walls of a pipe when the device is moved through the pipe, and means to move the 25 jaws forwardly to closed position.

30 15. In a device of the class described, a body having sides connected by a web portion, the edges of the sides of the web portion converging at their ends, two jaws 35 mounted on the body, and means to move the jaws together to grip an obstruction.

35 16. In a device of the class described, a body having sides connected by a web portion, the edges of the sides of the web portion converging at their ends, two jaws 40 mounted on the body, means to move the jaws together to grip an obstruction, and a flexible member secured to the body member for moving the latter in a pipe.
